UNITED STATES PATENT OFFICE.

EDWARD O. MILLHOUSER, OF KANSAS CITY, MISSOURI.

RAILWAY-CROSSING SIGNAL.

Application filed December 13, 1924. Serial No. 755,713.

To all whom it may concern:

Be it known that I, EDWARD O. MILLHOUSER, a citizen of the United States, residing at Kansas City, in the county of Jackson, son and State of Missouri, have invented certain new and useful Improvements in Railway-Crossing Signals, of which the following is a specification.

My invention relates to new and useful improvements in railway signals and the primary object is the provision of signals of the character stated which are particularly adapted for use at railway crossings to give both visual and audible signals or alarms as trains approach the crossing.

A further object of the invention is the provision of a railway signal which can be readily installed wherever desired along the track without necessitating altering the track construction, and which will be positively operated by the rolling stock traveling on the track.

Other objects will hereinafter appear, and in order that the invention may be fully understood reference will now be had to the accompanying drawings, in which:

Fig. 1 is a broken plan view of a portion of a track equipped with the railway signal structure.

Fig. 2 is a broken side elevation of the mechanism shown by Fig. 1.

Fig. 3 is a broken detail side elevation, partly in section, of a portion of the wheel-actuated mechanism.

Fig. 4 is an enlarged cross section on line IV—IV of Fig. 1.

Fig. 5 is an enlarged longitudinal section on line V—V of Fig. 1.

Fig. 6 is a broken plan view of a section of the railway track equipped with a modified form of the signal structure.

Fig. 7 is a side elevation of the parts disclosed by Fig. 6.

Fig. 8 is an enlarged broken section on line VIII—VIII of Fig. 6.

Fig. 9 is a cross section on line IX—IX of Fig. 8.

Referring now in detail to the various parts, 2 designates in general a track section including the rails 4 secured upon the cross ties 6.

8 designates a signal post arranged beside the track at a railway crossing or other desired point. Said signal post 8 is equipped

55 with a signal light 10 connected to a normally open circuit 12 including a battery

14 and a circuit breaker embodying a stationary contact 16, fixed to the post 8, and a movable contact 18 secured to an oscillatory lever 20.

The signal post 8 is also equipped with an audible signal in the form of a gong or bell 22, actuated by a hammer 24 secured to the lever 20, which has a horizontally extending arm 26 carrying a visual signal in the form of a flag 28.

The lever 20 is normally held against a stop 30 on the signal post 8 by yieldable means such as a coil spring 32 connected at one end to one of the cross ties 6 and at its opposite end to a crank 34 fixed to the transverse shaft 36 of the lever 20. The transverse shaft 36 is rockably mounted in bearings 38 secured to the lower portions of the rails 4.

Located along the track at a suitable distance from the signal post 8 is a wheel-actuated member 40 in the form of a bow spring, the terminals of which are slidably mounted in shoes 42 secured upon the adjacent cross ties 6. As shown by Figs. 1 and 4, the member 40 is located adjacent to one of the rails 4, so that the flanges on the wheels of the rolling stock may run upon the arched portion of said member and depress the same. In order to prevent the member 40 from springing laterally from beneath the wheel flanges, said member is provided with an upturned flange 44, which lies against the inner side of the ball of the adjacent rail 4, so that it will be between said rail and the wheel flanges as the same travel upon and depress the member 40.

A plunger in the form of a rack 46 extends downwardly from the raised central portion of the member 40 and into a guide 48 which is sunk into the road bed and encloses a pinion 50, which intermeshes with the teeth of the rack 46. The pinion 50 is fixedly mounted upon a crank shaft 54 journaled in the upper portion of the guide 48 and bearings 56, which latter are secured to the rails 4. A crank 60 at one end of the shaft 54 is connected to the crank 34 by a cable 62, which is enclosed the greater portion of its length in a protective conduit 64 secured upon the adjacent cross ties 6.

With the parts arranged as shown and described it is apparent that as the flanges of the wheels of the rolling stock intermittently depress the member 40 it will in turn depress the plunger 46 which causes

the pinion 50 to rotate counter-clockwise. As the pinion 50 rotates counter-clockwise it causes the crank shaft 54 to pull the cable 62 to the left, Fig. 2, which in turn 5 pulls the lever 20 therewith, causing the same to move the flag 28 and carry the hammer 24 forcibly against the gong 22, sounding the same. The movable contact 18 also closes the circuit 12 by engaging 10 the contact 16, thereby causing the light 10 to glow. The instant the flange of each wheel leaves the member 40 the same springs up to normal position, the spring 32 restores the lever 20 against the stop 30 15 and the circuit 12 is interrupted by the contact 18 swinging away from the contact 16. Thus it will be understood that the alternate action of the spring 32 and the cable 62, will cause the lever 20 to oscillate, 20 causing the flag 28 to wave, the hammer 24 to sound the gong 22, and the light 10 to intermittently glow until the train has passed.

In the modified form disclosed by Figs. 25 6 to 9, inclusive, the parts are substantially the same as in the preferred form, as evidenced by corresponding reference characters with exponents *a*, the chief difference being that the wheel-actuated member 40 30 is secured at one end to one of the cross ties 6^a and has its opposite end pivotally connected to a crank 52^b of the crank shaft 54^a, while the arched portion of said member 40^a, has a plunger 46^a operating in a 35 guide 48^a sunk in the road bed and secured to the two adjacent cross ties 6^a. As the member 40^a is depressed by the wheel

flanges it moves longitudinally in the direction of the crank 52^b, which is thereby caused to actuate the crank shaft 54^a, which in turn actuates the signals through the intervening mechanism. As the member 40^a moves longitudinally, as stated, it carries the plunger 46^a therewith, so the guide 48^a is made elliptical in cross section as shown 45 by Fig. 9, to permit of such movement.

While two forms of the invention have been disclosed, I reserve the right to make such other forms and changes in the details of construction, combination and arrangement of parts as properly fall within the spirit and scope of the invention as claimed.

Having thus described my invention, what I claim and desire to secure by Letters Patent, is:

A railway signal structure consisting of a signal, yieldable means for retaining said signal in normal position, a cable for operating said signal, a wheel-actuated member to effect the operation of said cable and having a resilient arched portion arranged in the path of wheels running on an adjacent rail, and an upwardly projecting flange on said member for engagement by the adjacent sides of the wheel flanges to prevent lateral displacement of said member.

In testimony whereof I affix my signature, in the presence of two witnesses.

EDWARD O. MILLHouser.
